UNITED STATES PATENT OFFICE.

ADOLF WENDT, OF BERLIN, GERMANY, ASSIGNOR TO DEUTSCHE GOLD- UND SILBER-SCHEIDEANSTALT VORMALS ROESSLER, OF FRANKFORT-ON-THE-MAIN, GERMANY.

ANGLED HANDPIECE FOR DENTAL PURPOSES.

Application filed October 17, 1927, Serial No. 226,787, and in Germany October 21, 1926.

This invention relates to an angled hand piece for dental purposes, that is to say, a tool in which the axis of the cutter or bit is at an angle to the axis of the driving shaft, for 5 the purpose of enabling boring or similar operations to be carried out by the tool on parts of the work which could not be operated on, or only operated on with great difficulty, by the more usual tool having the axis of 10 the cutter or bit in alignment with the axis of the driving shaft.

The invention has particular reference to angled hand pieces, in which the retaining socket or carrier for the bit or tool proper 15 is mounted on rolling bodies in the tool head.

According to the present invention the retaining socket or carrier for the bit or tool proper is constructed in parts, adapted 20 to be screwed together, and it is also formed with channels or races to provide in conjunction with corresponding channels or races formed in the head, cages for balls or rollers between the retaining socket or carrier and the head.

25 The drive is imparted to the retaining socket or carrier by means of a crown wheel and a pinion meshing therewith, and another feature of the invention consists in that the pinion is mounted on the externally screw-threaded part of the retaining socket or carrier, the inner end of the other or internally screw threaded part of the retaining socket or carrier thus forming an abutment to prevent undue axial movement of the pinion.

30 The invention further includes the provision of a sleeve, within the retaining socket, to receive the cutter or bit, this sleeve having a conical and split end for cooperation with a conical face formed in a screw-plug, which 35 is screwed into the adjacent end of the retaining socket, so that by screwing up or unscrewing the plug, its conical face is caused to bear on or recede from the conical split end of the sleeve and so cause the sleeve to grip the cutter or bit inserted therein or to release it, as the case may be.

The sleeve may, however, have both ends split and coned, in which case the end remote 40 from the plug cooperates with an inner conical face formed on the adjacent end of the retaining socket.

Under these conditions when the cutter or bit is inserted in the socket, and the plug is screwed into the end of said socket, the split ends of the socket are forced inwardly 55 by sliding engagement between the cooperating conical faces at each end of the socket, and the cutter or bit is thus gripped by both ends of the socket.

It is to be understood, however, that although the invention includes the aforesaid gripping sleeve, it is not restricted to the use of the sleeve for the purpose, as any other suitable gripping means may be substituted therefor without departing from the invention.

One form of an angled hand piece constructed in accordance with the invention is shown by way of example in the accompanying drawing, in section.

In the drawing *a* is the head of the tool, in the form of a sleeve having a stem in which the driving shaft is mounted.

This head or sleeve *a* is formed with two internal ribs *b* presenting curved or channeled faces, as shown, to form outer races for balls *c*.

A retaining socket or tool carrier *d* is arranged within the head *a*.

This retaining socket *d*, is formed in two parts *f* and *g*, having their inner ends screw-threaded for screw-threaded engagement one within the other.

The outer ends of these parts *f* and *g* are enlarged or flanged to close the open ends of the head or sleeve *a* and they each present a curved or channeled face, these curved or channeled faces forming inner races for the balls *c*.

It will thus be appreciated that each set of 90 balls is mounted in a cage constituted by the opposed upper and lower races.

The drive is transmitted from a motor by a crown wheel *i* meshing with a pinion *k*, which is screwed on the exteriorly threaded 95 part *g* of the retaining socket *d* and is prevented from undue axial movement by the inner end of the interiorly screw threaded part *f* of said socket.

A sleeve *m* is arranged in the retaining 100 socket *d* to receive the shank of the tool.

This sleeve, in the example illustrated, is

slotted at both ends as at *n* and is provided at these slotted ends with conical enlargements *s* and *t* respectively.

The conical enlargement *s* at one end co-
5 operates with a conical face *r* formed on a screw plug *o*, which is screwed into the outer end of the part *f*, this end having a screw thread *p* formed therein for the purpose, while the conical enlargement *t* at the other end of the sleeve *m* co-operates with a conical face *u* formed in the outer end of the part *g* of the retaining socket *d*.

When the plug *o* is screwed into the part *f* its conical face *r* will bear on the conical end 15 *s* of the sleeve *m* thus tending by pressure to reduce the diameter of this split end.

At the same time a longitudinal movement will be imparted to the sleeve by this engagement, thus causing the conical end *t* to slide 20 along the conical face *u* at the other end of the sleeve, thereby reducing the sleeve in diameter at this other end, which is also split.

On further screwing up of the plug *o* both 25 split ends of the sleeve will be reduced in diameter thus tightly gripping the shank of a cutter or bit inserted in the sleeve, both at its outer end and towards its inner end.

If preferred only the end of the sleeve *m* adjacent to the plug *o* may be split and coned 30 so that gripping of the cutter or bit takes place at this end only, the remainder of the sleeve being plain and serving to house the shank of the cutter or bit.

The reference letter *c* indicates the openings left by the annular ribs *b*, to permit of 35 assembly.

It will be readily appreciated that the construction hereinbefore described permits of assembly and dismantling of the device as a 40 whole by merely screwing together or separating by unscrewing the parts *f* and *g* constituting the retaining socket *d*.

Moreover, by screwing up or unscrewing the parts *f* and *g* to effect relative axial 45 placement, correct centering of the carrier *d* is effected automatically, the two parts *f*, *g* thereof being adjusted simultaneously.

It will also be appreciated that the construction according to the invention, avoids 50 stationary parts projecting from the socket so that satisfactory working with the tool is ensured.

I claim:

1. An angled hand piece for dental purposes comprising a head casing, annular ribs on the interior of said casing, a tool carrier consisting of two parts screwed together at their inner ends and arranged in said casing, annular enlargements at the outer ends of 55 said parts forming said tool carrier, balls between the ribs in said casing and the enlargements on said carrier for bearing said carrier in said casing, and means to drive said carrier.

2. An angled hand piece for dental pur-

poses comprising a head casing, annular ribs on the interior of said casing, a tool carrier consisting of two threaded parts screwed together within said casing, annular enlargements at the ends of said parts forming said 70 tool carrier, balls between at least one of said ribs in the casing and its corresponding enlargement on said carrier for bearing said carrier in said casing, a pinion screwed on the externally threaded part of said carrier, and means on the driven shaft of the hand piece in meshing engagement with said pinion.

3. In a hand piece for tools, a hollow, substantially T-shaped casing consisting of a head and a handle, a pair of annular ribs formed on the inside of said head, a tool carrier consisting of two parts, one of said parts having the inner end threaded internally and the other of said parts having an externally threaded inner end, both inner ends having lesser diameters than the inner diameters of the ribs and hence being adapted to be inserted from the opposite ends of the casing head and screwed together, annular enlargements on the outer ends of said parts of the tool carrier, balls disposed between at least one of said enlargements and the corresponding annular rib, a rotatable member secured upon the inner end of one of said parts, and driving means within the handle portion of the casing and in engagement with said rotatable member.

4. An angled hand piece for dental purposes comprising a head casing, annular projections in the interior of said casing, a tool carrier consisting of two parts screwed together arranged in said casing, annular projections at the ends of said parts forming said tool carrier, balls between said projections in said casing and on said carrier for bearing said carrier in said casing, a sleeve in said carrier, said sleeve being of shorter length than the carrier, axial slots at one end of said sleeve, conical enlargements at said slotted end, a screw plug in one of said parts forming said carrier, a conical face on said screw plug cooperating with said conical enlargements of said sleeve, a pinion screwed on the externally screwed part of said carrier, and a wheel meshing with said pinion and arranged on the driven shaft of the hand piece.

5. An angled hand piece for dental purposes comprising a head casing, annular projections in the interior of said casing, a tool carrier consisting of two parts screwed together arranged in said casing, annular projections at the ends of said parts forming said tool carrier, balls between said projections in said casing and on said carrier for bearing said carrier in said casing, a sleeve in said carrier, said sleeve being of shorter length than the carrier, axial slots at both ends of said sleeve, conical enlargements at 120

said slotted ends, a screw plug in one of said parts forming said carrier, a conical face on said screw plug cooperating with one of said conical enlargements of said sleeve, a conical

screwed on the externally screwed part of said carrier, and a wheel meshing with said pinion and arranged on the driven shaft of 10 the hand piece.

5 face in the other of said parts forming said carrier and cooperating with the other conical enlargement of said sleeve, a pinion

In testimony whereof I affix my signature.

ADOLF WENDT.
